UNITED STATES PATENT OFFICE.

CHARLES G. SUMMERS, OF BALTIMORE, MARYLAND.

DESIGN FOR A JELLY-GLASS.

SPECIFICATION forming part of Design No. 12,729, dated January 31, 1882.
Application filed January 3, 1882. Term of patent 2½ years.

To all whom it may concern:

Be it known that I, CHARLES G. SUMMERS, of Baltimore city, in the State of Maryland, have invented a new and useful Design for a Jelly-Glass or Analogous Article of Glassware; and I do hereby declare that the following is a true specification thereof, reference being had to accompanying drawing, forming part thereof, in which is represented a perspective view of a jelly-glass bearing my design.

The individual features of the design are, first, a series of squares whose surfaces are alternately rough and plain with a cross thereon; second, a medallion bearing the figure of an imperial crown; third, a series of the aforesaid squares and a top ornauent in the form of an imperial crown applied to the lid or cover of the dish.

In the drawing, the letters A and B indicate the body and cover of the dish, respectively. a indicates the squares on the body A, which have roughened or frosted surfaces, and b those having plain surfaces with a Latin cross thereon, the cross being preferably in relief, as shown. Such squares are arranged in vertical and horizontal rows on the sides of the glass A, the rough-surfaced ones alternating with the plain. The medallion occupies an intermediate position. In other words, it is flanked on each side by a series of said squares, a b. An imperial crown, d, is located in the center

of the medallion—that is to say, of the tablet, inclosed by the border e. Both the crown and border are in relief, but may be intaglio, if preferred. The cover B has a circle of alternating plain and rough-surfaced squares, a' b', near its edge, and in the center rises an ornauent in the form of an imperial crown, f.

What I claim is—

1. The design for a jelly-glass whose body has a series of rough-surfaced squares, a, alternating with plain-surfaced squares b, having a cross thereon, a medallion and crown, and a series of such roughened and plain-surfaced squares, and the crown f, applied to the cover, as shown.
2. The design for a jelly-glass, consisting of the squares a and b, having alternating roughened surfaces and plain surfaces, with a cross and a medallion bearing an imperial crown, as shown and described.
3. The design for a jelly-glass, consisting of squares having alternately roughened surfaces and plain surfaces, with a cross, as shown and described.
4. The design for a jelly-glass, consisting of a medallion bearing an imperial crown, as shown and described.

CHARLES G. SUMMERS.
